CLAIM

The ornamental design for a "sleeping bag with pocket for toy", substantially as shown and described.

DESCRIPTION

FIG. 1 is a top plan view of the sleeping bag with pocket for toy;

FIG. 2 is a bottom plan view thereof;

FIG. 3 is an enlarged front elevational view thereof;

FIG. 4 is an enlarged rear elevational view thereof;

FIG. 5 is a left side view thereof; and,

FIG. 6 is a right side view thereof.

The broken line showing the toy inside the pocket in FIGS. 1, 3, 4 and 5 and the broken line showing a zipper in FIGS. 4 and 5 are for illustrative purposes only and forms no part of the claimed design.
